UNITED STATES PATENT OFFICE.

KARL KARLSON, OF BROOKLYN, NEW YORK, ASSIGNOR OF ONE-HALF TO GEORGE J. F. WILFORD, OF NEW YORK, N. Y.

FUNNEL.

1,113,648.

Specification of Letters Patent.

Patented Oct. 13, 1914.

Application filed November 6, 1913. Serial No. 799,632.

To all whom it may concern:

Be it known that I, KARL KARLSON, a subject of the King of Sweden, residing at Brooklyn, in the county of Kings and State 5 of New York, have invented certain new and useful Improvements in Funnels, of which the following is a specification.

This invention relates to a funnel, and the principal object of the invention is to 10 provide a funnel which is so constructed that a valve will be automatically opened when the funnel is placed in a bottle or other receptacle and automatically closed when the bottle or receptacle has been filled 15 to the desired amount.

Another object of the invention is to provide an improved means for actuating the valve when the bottle is filled.

Another object of the invention is to 20 so construct the funnel that it will be supported in the desired position in the bottle neck.

This invention is illustrated in the accompanying drawings wherein there is 25 shown a sectional view of the improved funnel mounted in a bottle which is also shown in section.

This funnel 10 is provided with an outlet spout 11 the funnel being removably connected with the outlet by means of a valve seat 12 which has an externally threaded lower end portion 13. A gate valve 14 is hinged to the valve seat and is intended to close the opening 15 when moved to its 35 lowered position. A bell-crank lever 16 is pivotally mounted upon a support 17 in the outlet spout 11 and is connected with the gate valve 14 by means of the link 18. A float 19 has its supporting rod 20 passed through 40 a guide 21 and through the support 17 with its inner-end portion bent to form a hook 22 which engages the shorter arm of the bell-crank lever 16 when the valve is in the raised position as shown in the drawing. An abutment 23 is carried by the rod 20 to prevent the float from moving upwardly beyond a desired point. A U-shaped opening element for the valve is slidably connected with the outlet spout 11 by having 45 its outer arm 25 passed through the guides 26 and 27 and its inner arm 25' passed through the guide 28. The upper end portion 29 of the outer arm is bent as shown to engage the top of the bottle neck 30 50 when the funnel is inserted in the bottle

or other receptacle. A collar 31 is carried by the outlet spout 11 and forms a support for the funnel and an abutment to limit the upward movement of the valve-opening device 24. A finger 32 is pivotally connected with the upper end of the inner arm 25' and is so mounted that it may move upwardly into alignment with the arm 25', but can not move downwardly beyond the position shown in the drawing. 65

The operation of this device is as follows: When the funnel is not in use, the valve-opening device is in the dotted-line position shown in the drawing with the finger positioned beneath the lower end of the 70 long arm of the bell-crank lever 16. The valve 14, of course, is closed when the funnel is not in use. When the funnel is inserted in the neck of the bottle, the upper end portion 29 of the outer arm 25 engages 75 the bottle neck and as the funnel is inserted in the neck, the finger 32 engages the bell-crank lever and moves the lever upwardly so that the gate valve 14 will be raised. Said bell crank lever raises the 80 shorter arm and the same moves beneath the hook 22 and the longer arm of the lever will then be raised a greater extent until the finger 32 passes beyond the joint between the bell crank lever and rod 18. The 85 weight of the valve 14 will then cause the bell crank lever to move to the position shown in the drawing with the hook 22 holding the same in the raised position. Liquid is poured into the funnel and passes 90 through the funnel into the bottle. When the liquid in the bottle reaches the float 19, it will raise the float and thus raise the hook out of engagement with the bell-crank lever so that the gate valve can fall to a 95 closed position and thus prevent any more liquid from passing into the bottle. The funnel can now be removed and the valve-opening device will fall to the lowered position and be again ready for use when desired. It is of course obvious that when the valve opening device drops to a lowered position, the finger 32 will swing upwardly when passing the end of the bell crank lever and will then return to its normal position 100 so that it may engage the bell crank lever to engage the same when the funnel is inserted in a second bottle. 105

What is claimed is:

1. A funnel, a valve seat in said funnel, 110

a valve carried by said seat, a bell-crank lever pivotally mounted in said funnel beneath said valve seat, a link connecting said valve with one arm of said lever, a rod slidably mounted in said funnel with its upper end bent to form a hook for engaging the remaining arm of said bell-crank lever, a float carried by said rod, a U-shaped valve-setting device slidably connected with said funnel with one arm extending into the funnel and the remaining arm extending outside said funnel and having its upper end portion bent to form an abutment finger, and a finger pivotally connected with the inner arm of said valve-setting device and engaging said bell-crank lever to move said valve to an open position.

2. A funnel, a valve seat in said funnel, a valve, actuating means for said valve, a float, means carried by said float for releasably engaging said actuating means for releasably holding said valve in an open position, a U-shaped member slidably connected with said funnel having one arm extending into said funnel for engaging said actuating means to move said actuating means and opening said valve when said member is moved to its raised position, the

outer arm of said member being bent to engage a bottle neck when a funnel is inserted in a bottle to move said member to its raised position, and means carried by said funnel for limiting the raising movement of said member and supporting said funnel in a receptacle.

3. A funnel provided with a valve seat, a valve, actuating means for said valve, means including a float releasably engaging said actuating means for releasably holding said valve in an open position, a member slidably connected with said funnel and having its inner portion provided with a movably mounted element engaging said actuating means to move said actuating means and open said valve when said member is moved to a raised position, and the outer portion of said member being provided with means for engaging a receptacle to raise said member when said funnel is placed in a receptacle.

In testimony whereof I affix my signature in presence of two witnesses.

KARL KARLSON.
